UNITED STATES PATENT OFFICE

KRAFT BOOTH, OF PHILADELPHIA, PENNSYLVANIA, ASSIGNOR TO
GILLINDER & SONS, A CORPORATION OF PENNSYLVANIA.

DESIGN FOR GLASS-MAKER'S STOCK.

SPECIFICATION forming part of Design No. 36,098, dated October 7, 1902.

Application filed September 9, 1902. Serial No. 122,744. Term of patent 14 years.

To all whom it may concern:

Be it known that I, KRAFT BOOTH, a citizen of the United States, residing in the city and county of Philadelphia, State of Pennsylvania, have invented and produced a new, original, and ornamental Design for Glass-Makers' Stock, of which the following is a specification, reference being had to the accompanying drawings, forming part thereof.

5 The leading feature of my design for glass-makers' stock is a surface of alternating festoons and pendants.

Figure 1 represents a face view of a piece of glass-makers' stock embodying my design.

10 Fig. 2 represents a section thereof on line xx , Fig. 1.

In the drawings, A designates a piece of glass-makers' stock, the same having thereon the rows of alternating festoons B and pendants C. The surface of the piece between 20 the festoons and pendants is picked, as at D.

Having thus described my invention, what I claim as new, and desire to secure by Letters Patent, is—

The ornamental design for glass-makers' 25 stock substantially as shown and described.
